DESIGN FOR A COMBINED PICTURE HOOK AND NAIL

Max Rubel, New York, N. Y.

Application July 15, 1937, Serial No. 70,470

Term of patent 14 years

To all whom it may concern:

Be it known that I, Max Rubel, a citizen of the United States, residing at New York city, in the county of New York and State of New York, have invented a new, original, and ornamental Design for a Combined Picture Hook and Nail, of which the following is a specification, reference being had to the accompanying drawing, forming part thereof, in which:—

I claim:—

The ornamental design for a combined picture hook and nail, as shown.

MAX RUBEL.
